Phinney-Walker Co. Inc., New York, N. Y., a
corporation of New York

Application November 4, 1939, Serial No. 88,045

Term of patent 14 years

To all whom it may concern:

Be it known that I, John P. Ambrose, a citizen
of the United States, residing at Bronx county of
Bronx, State of New York, have invented a new,
original, and ornamental Design for a Pull Wind
Panel Clock, of which the following is a specifi-
cation, reference being had to the accompanying
drawing, forming part thereof.

Fig. 1 is a face view of a pull wind panel clock
showing my new design.

Fig. 2 is a back view and

Fig. 3 is an edge or end view.

I claim:

The ornamental design for a pull wind panel
clock, substantially as shown.

JOHN P. AMBROSE.
